No. 828,410.

PATENTED JUNE 12, 1906.

C. A. HOFF.
WINDMILL LUBRICATOR.
APPLICATION FILED DEC. 26, 1905.

UNITED STATES PATENT OFFICE.

CHARLES A. HOFF, OF BLAIR, NEBRASKA.

WINDMILL-LUBRICATOR.

No. 823,410.

Specification of Letters Patent.

Patented June 12, 1906.

Application filed December 26, 1905. Serial No. 283,358.

To all whom it may concern:

Be it known that I, CHARLES A. HOFF, a citizen of the United States, residing at Blair, in the county of Washington and State of Nebraska, have invented a new and useful 5 Windmill-Lubricator, of which the following is a specification.

My invention relates to improvements in windmill-oilers in which a reservoir to carry 10 a supply of lubricant is located at the top or head of the mill; and the objects of my improvement are, first, to force a supply of semifluid or hard-oil lubricant from the reservoir to the different stationary and traveling 15 bearings of the machine without climbing the tower; second, to facilitate the conduction of the lubricant from the reservoir to the wearing parts by a novel construction of flexible or jointed pipes and by conduits or ducts in 20 the stationary and movable parts of the windmill machinery itself. I attain these objects by the mechanism illustrated in the accompanying drawings, in which—

Figure 1 is a rear elevation of a part of a 25 windmill with my invention applied, shown partly in vertical section on the broken line *a* of Fig. 4. Fig. 2 is a whole side elevation of the same. Fig. 3 is a plan of the rocker-arm 2 with its various connected parts. Fig. 30 4 is a plan of the removable top of the reservoir and the feed mechanism, and Fig. 5 illustrates an adaptation of the piping to different types of windmill construction.

Similar numerals refer to similar parts 35 throughout the several views.

Numerals from 1 to 9, inclusive, refer to parts of the windmill, and numerals 10 and upward refer to the lubricator.

The common type of windmill chosen for 40 illustrating my invention consists of the vertical sleeve 9, to revolve around the top end of a pipe projecting up into it from the top of the supporting-tower below. This vertical sleeve 9 has an integral horizontal tube 6, 45 in which turns the main shaft carrying the wind-wheel at its outer or front end and the spur-pinion 3 at its inner or rear end to engage and revolve the large crank gear-wheel 4, mounted on a short shaft disposed in the 50 horizontal integral tube 5. The sleeve also has the integral upward and laterally-projecting arm 1, to the end of which is hinged the base of the rocker-arm 2. By the pitman 8 the swinging end of the rocker-arm is connected at one side with the wrist 4' on the gear-wheel 4, and to the other side of the

swinging end of the arm the pump-rod 7 is connected to reciprocate vertically through the pipe-support within the sleeve 9, as shown in Figs. 1 and 2.

The curved bar 22 has its lower end bolted to the arm 1. On the upper end of this bar is seated and fastened the lower head of the cylinder-reservoir 20, which is thus supported directly above the machinery. The pipes 65 which convey the lubricant to the different parts of the mill are connected through this lower head.

The upper head 15 of the cylinder or reservoir is removable to facilitate filling the reservoir with the lubricant. To this head the 70 force-feed mechanism and the canopy 18, to shield it from the weather, are attached.

A piston-head 21 is disposed in the cylinder-reservoir and is actuated by the piston-rod 10, disposed loosely through the head 15. 75 The upper half of this piston-rod is square in cross-section and slides loosely up and down through a square opening to guide and prevent it from turning in the upper horizontal part of the bar 17. This bar is attached to the head 15 and also supports the canopy 18. The lower half of the piston-rod is threaded through the pin-toothed wheel-nut 11, which when turned actuates the piston-rod endwise. 80 A sleeve 19 envelops the piston-rod between the guide-bar 17 and the wheel-nut to prevent the nut from raising when it is turned forward to compress the charge of lubricant 85 in the reservoir. 90

The oscillating bar 13 is centrally pivoted on an integral lateral projection 16 from the removable head 15. In its inner end is pivoted the pawl 12, having its free end forked or notched to engage the pin-teeth on the 95 periphery of the wheel-nut. The outer end of the bar 13 is provided with the counter-weight 14, which raises the inner end against the weight of the wire or cord 23 and draws back the pawl into position for an impulse 100 on the pin-toothed wheel-nut 11. The pawl 12 and the inner end of the bar 13 form a toggle or knee movement actuated by the line 23, which is attached near the joint and usually suspended by the side of the pump-rod through the pipe within the sleeve 9, thence down to the ground where it is grasped by the operator. 105

For lubricating parts of the machinery which remain stationary in position with reference to the reservoir—as, for instance, the shaft-bearings and boxing in the tubes 5 and 110

6—direct pipes, as 38' and 39, may be employed. Their lower ends may be branched laterally to the boxings at opposite ends, as shown, or with a single direct connection to the vacant space surrounding the shaft within the tube between the opposite end boxings or babbiting.

The hinge-pin 27, by which the base of the rocker-arm 2 is pivoted to the arm 1, is usually set rigidly through the end of the arm 1, the eyes at the ends of the branches of the forked base of the rocker-arm turning on the end portions of the pin at each side of the arm 1, as shown in Fig. 3. For this pin I use 15 a longitudinally-bored bar or piece of pipe with the forward end plugged. The rear end of the pin projects beyond the bearing and is provided with the opening 26' on top of the projecting end, by which the lower end of the 20 supply-pipe 26, leading from the reservoir above, is connected. Oil-holes 28 and 29 through the shell of the pin within the boxes supply these bearings with the lubricant. The pin 30, which forms the stud-journals by 25 which the top ends of the pump-rod and pitman are pivoted to the swinging end of the rocker-arm, is rigidly set through the end of the rocker-arm. In similar manner to the hinge-pin 27 I use for this purpose a hollow 30 pin and supply it with lubricant through the pipe 24, connected to its rear end. This pipe 24 leads from the rear end of the hinge-pin 27, to which it is connected by the union-joint pipe-coupling 25. This union-joint 35 pipe-coupling serves as a hinge or flexible joint in the pipe and allows the end of the pipe 24 that is connected to the pin 30 to swing up and down with the arm 2 independent of the stationary hinge-pin 27, to which 40 its opposite end is coupled. A small key-pin 40 is driven into a perforation through the threaded connection of the union-joint to prevent it from unscrewing and compel the bending movement to take place in the gasketed ground seat of the union-joint. This 45 seat is kept well oiled by the passing flow of the lubricant. In a like manner to the hinge-pin the oil-holes 31 and 32 in the top of the pin 30 supply the lubricant to the journal-boxes 7' and 8' at the tops of the pump-rod and pitman. The oil-hole 32 is elongated with the circumference of the pin or in the direction of the movement of the journal-box 8' on the pin, as shown. This is for the 50 purpose of offering a free opening at all points of movement for the flow of the lubricant into the end of the pipe 37, which is connected to the top of the journal-box 8' and is coupled to the pipe 38, below which leads the lubricant 55 down to the box on the wrist 4' in the lower end of the pitman. In some types of mills exactly this manner of piping the lubricant is impracticable. Then instead of the pipe 24, with the single union-joint coupling 60 65 25, I substitute the construction illustrated

in Fig. 5. This is a more extended application of the same principle. Here the lubricant is conducted directly in an independent line from the reservoir to the bearings on the movable end of the rocker-arm. I use three 70 sections of rigid pipe 42, 43, and 44, besides the part 37, disposed in angular form, as shown, and connected together by three union-joint pipe-couplings 45, 45, and 45. These are like the union-joint pipe-coupling 75 25 and have their threaded connections fastened by the key-pins 40, 40, and 40. This supplies a flexible duct from the reservoir to accommodate the vertical movement of the swinging end of the rocker-arm. By supplying 80 its vertical ends 37 and 44 with like union-joint pipe-couplings to rotate in horizontal planes I would have a pipe admitting of any direction of movement.

It is obvious that pulling and relaxing the 85 line 23 at alternate short intervals would rotate the wheel-nut 11 and move the piston-head downward, forcing the lubricant out through all the connected pipes to the machine-bearings.

By removing the head 15, which is simply bolted on, the reservoir is recharged. The pawl is raised and the pin-toothed wheel-nut revolved backward with the fingers until the piston-head is drawn up to its under side, 95 when the head may be replaced on the filled reservoir.

I claim—

1. The combination of a cylindrical reservoir, a piston in said reservoir, a square piston-rod, a support having a square aperture to receive the piston-rod, and a nut threaded on said piston-rod.

2. A force-feed machine-lubricator having in combination, a cylindrical lubricant-reservoir with ducts leading to the machine-bearings, a piston in said reservoir, the piston-rod having a threaded part and a part square in cross-section disposed loosely through a square guide-aperture in a support-bar, a nut 105 mounted on the threaded part of the piston-rod between the piston-head and support-bar.

3. A force-feed windmill-lubricator having in combination a cylindrical lubricant-reservoir in communication with the mill-bearings, a piston fitted in the reservoir, the piston-rod having a threaded portion and a part square in cross-section, a bar attached to said reservoir and having a square aperture to 110 loosely receive and guide the square part of the piston-rod, a pin-toothed wheel-nut mounted on the threaded part of the piston-rod between the guide-bar and the piston-head, a toggle-jointed gravity-return pawl to 115 engage the pin-toothed wheel-nut and a line connected to actuate the pawl.

4. A force-feed windmill-lubricator having in combination a cylindrical lubricant-reservoir with ducts leading to the bearings of the 120

- mill, a piston in the reservoir, the piston-rod having a threaded part and a part square in cross-section, a support-bar having a square aperture to loosely receive the square part of the piston-rod, a pin-toothed wheel-nut mounted on the threaded part of the piston-rod and a sleeve-strut interposed between the wheel-nut and the support-bar on said piston-rod.
5. A force-feed windmill-lubricator having in combination a cylindrical lubricant-reservoir with communicating ducts leading to the bearings of the mill, a piston in said reservoir, the piston-rod having a threaded part and a part square in cross-section, a support-bar having a square aperture to loosely receive the square part of the piston-rod, a pin-toothed wheel-nut mounted on the threaded part of the piston-rod and a sleeve-strut interposed between the wheel-nut and the support-bar on said piston-rod.
10. 5. A force-feed windmill-lubricator having in combination a cylindrical lubricant-reservoir with communicating ducts leading to the bearings of the mill, a piston in said reservoir, the piston-rod having a threaded part and a part square in cross-section, a support-bar having a square aperture to loosely receive the square part of the piston-rod, a pin-toothed wheel-nut mounted on the threaded part of the piston-rod and a sleeve-strut interposed between the wheel-nut and the support-bar on the piston-rod, a gravity-return knee-jointed pawl to engage the pin-toothed wheel-nut and a dependent line connected to actuate the pawl.
